(57) **CLAIM**

The ornamental design for an ottoman, as shown and described.

DESCRIPTION

FIG. 1 is a top perspective view of an ottoman showing our new design.

FIG. 2 is a front view of the ottoman shown in FIG. 1.

FIG. 3 is a rear view of the ottoman shown in FIG. 1.

FIG. 4 is a left side view of the ottoman shown in FIG. 1.

FIG. 5 is a right side view of the ottoman shown in FIG. 1.

FIG. 6 is a top view of the ottoman shown in FIG. 1; and,

FIG. 7 is a bottom view of the ottoman shown in FIG. 1.

The ottoman is shown with multiple symbolic breaks in its length and width, illustrated by zig-zag dashed lines. The zig-zag dashed lines represent unclaimed boundaries. The appearance of any portion of the article between the break lines forms no part of the claimed design.
